(57) **CLAIM**

The ornamental design for a plant stand weight, as shown and described.

DESCRIPTION

FIG. 1 is a perspective view of a plant stand weight in accordance with the present design.

FIG. 2 is a right side view of the plant stand weight.

FIG. 3 is a left side view of the plant stand weight.

FIG. 4 is a front view of the plant stand weight.

FIG. 5 is a back view of the plant stand weight.

FIG. 6 is a top view of the plant stand weight.

FIG. 7 is a bottom view of the plant stand weight; and,

FIG. 8 is a perspective view thereof, showing the plant stand weight of FIG. 1 in use.

The broken lines in FIGS. 1, 6, 7, and 8 illustrate portions of the plant stand weight and form no part of the claimed design. The other broken lines in FIG. 8 represent environmental subject matter only and form no part of the claimed design.

1 Claim, 4 Drawing Sheets
